T.R. DEVICES

William Joseph Scott and Francis Lucas Crowther, Rugby, England, assignors to Associated Electrical Industries (Rugby) Limited, London, England, a British company

Filed Mar. 24, 1959, Ser. No. 801,477

Claims priority, application Great Britain Mar. 31, 1958

3 Claims. (Cl. 333—13)

This invention relates to T.R. devices of the kind used in connection with radar equipments utilising a common aerial system for transmission and reception for protecting the receiver of the equipment from the energy supplied to the aerial for the transmitter. Transmit-receive (T.R.) cells, transmitter-blocker (T.B.) cells and pre-T.R. cells are examples of such devices and will be collectively referred to hereinafter under the term T.R. devices.

T.R. devices of the kind to which the invention relates employ a resonant slot tuned to the frequency of the oscillations to be transmitted and received which is enclosed within an evacuated space containing, usually an inert gas such as argon plus some water-vapour. A common construction is to provide the slot in a metal diaphragm arranged transversely across a wave guide through which the oscillations are transmitted, the slot being filled with glass hermetically sealed to the metallic rim of the slot so as to form a resonant window, the diaphragm sealing off a section of the wave guide which is evacuated and filled with inert gas and water vapour as above stated or other arc quenching agent. When oscillations of high energy pass through the section of wave guide, an electric discharge occurs across the slot. If the energy so dissipated is not unduly high, no adverse effects are experienced; but if the energy dissipated is raised to a high value, the intense ionisation and products produced by the arc have been found to render the device unusable after a comparatively short space of working life.

The object of the invention is to improve the operation of T.R. devices of the kind above described by increasing their life.

A further object of the present invention is to prevent the products produced by the discharge across the slot from interacting with the metal in the vicinity of the slot and elsewhere in diffusing distance.

According to the invention an enclosure for the window constituting the resonant slot of a T.R. device is provided in the form of a member of vitreous material having a hollow in one face thereof, said member being located with the hollow facing the window and in proximity thereto so that the atmosphere within the device can enter the hollow and so that the inside of the enclosure is of glass or other vitreous material. The enclosure thus prevents the intense ionisation produced by the discharge from reaching the wall of the T.R. device and producing undesired arcing products.

The member may be in the form of a block of vitreous material having a concavity in one face thereof; alternatively the member may be in the form of a hollow box built up from parts of vitreous material.

The member may be retained in proximity to the window by means of projections from the internal wall of the T.R. device, against which the member abuts when the member is introduced into the device prior to the affixing of the frame containing the resonant slot as an end closure member of the device.

The projections may be made by nicking the inner wall of the device with a sharp instrument so as to produce burrs, or by narrow ledges brazed to the walls. In T.R. cells in which the resonant slot is provided in a transverse wall across a section of waveguide of rectangular cross-

section, a wide inductive iris spaced from the transverse wall may be arranged to support the block.

The invention will be better understood on consideration of the following description of the accompanying drawings, in which:

FIG. 1 shows in elevation and partly in cross section a T.R. cell of the kind embodied in a section of wave guide of rectangular cross section.

FIG. 2 is a cross section of FIG. 1 on the line II—II of FIG. 1.

FIG. 3 is a perspective view of the vitreous block shaped to form a protection for the resonant slot in the T.R. device.

FIG. 4 is an elevation partly in cross section of an alternative form of T.R. device embodying the invention, and

FIG. 5 is a cross section of a part of the T.R. device shown in FIG. 4 on the line V—V of FIG. 4.

The form of T.R. device illustrated in FIGS. 1 and 2 consists of a short section 1 of waveguide of rectangular cross section terminated by flanges 2 through which it can be connected to adjacent sections of waveguide. The section is sealed at its ends by transverse metal walls 3 each containing a window constituting a resonant slot 4, the longitudinal axis of which is parallel to the wider dimension of the waveguide section. The resonant slots are sealed by glass 5 hermetically sealed to the wall 3 at the rim of the opening therein and covering the near face of the adjacent wall around the slot, as is clearly shown in FIG. 1. Spaced from the wall 3 is formed an opening 6 or inductive iris limited by transverse walls 7 which extend inwardly from the narrow walls of the waveguide and by narrow projections 8 extending inwardly from the wider walls of the guide. Conical electrodes 9 between which a gap is present are provided in a manner customary with T.R. devices of the character illustrated, across which a discharge takes place when high frequency power greater than a predetermined value passes through the T.R. device.

In order to protect the window formed by the resonant slot 4 and the surrounding wall of the T.R. device from the effect of intense ionisation produced when oscillations of high energy pass through the section by the waveguide, there is provided in the neighbourhood of the slot an enclosure consisting of a block 10 or box 10 of vitreous material or of more than one vitreous material having a hollow in the form of a concavity 11 in one face thereof, the block being located with the concavity facing the window and in proximity thereto as illustrated. The block 10 is not integral with the glass 5 hermetically sealed in the window so that the atmosphere within the device can enter the concavity, the interior wall of the enclosure formed thereby being thus of glass or vitreous material which is inappreciably affected by the discharge across the window. The block 10 which is shown in perspective in FIG. 3 is preferably of fused silica and of rectangular form, where the waveguide section 1 is rectangular in cross section. The concavity 11 in the block may conveniently be in the form of a shallow depression of cylindrical contour bounded by side walls 12 which are substantially vertical to the planes containing the faces 13 of the block, the side walls 12 lying parallel to the wide dimension of the window. The depression 11 may be produced by grinding one face of a rectangular plate of fused quartz with a grinding or lapping wheel. The plate may have, for a T.R. device suitable for centimetric waves of 3.2 cm. wavelength, a length of the order of 0.9", a width of the order of 0.4" and a thickness of the order of 0.125", the depression reducing the thickness at the centre of the block to about 0.024". The depression is so located as to leave a plane rim around it having a width of about 0.032".

In the arrangement shown in FIGS. 1 and 2, the block is held firmly in position in proximity to the window by the wall 1 and the resilient partitions 8 forming the iris 6. The electrical function of the iris 6 is to tune out the capacity introduced by the shield formed by the block 10. The T.R. device is normally filled with a mixture of rare gas and water vapour, in which the discharge across the resonant slot takes place, for example, a filling of krypton at a pressure of 10 millimetres of mercury, and water vapour at a pressure of 4.5 millimetres of mercury may be employed.

In the arrangement shown in FIGS. 4 and 5, a different form of T.R. device is illustrated, the device consisting of a T.B. cell utilising the protective window of the invention. The cell consists of a section 14 of rectangular waveguide closed at one end by the transverse metal wall 15 containing the sealed resonant aperture or window 4 in proximity to which the block 10 is located. The far end of the section of waveguide is completed by a mounting flange 16 through which passes an evacuating tubulation 17. In this construction means for tuning the window to resonance at a predetermined frequency is illustrated, consisting of a flexible metallic diaphragm 18 which is placed over the window and is secured to the broad walls of the waveguide section 14, e.g. by brazing. The diaphragm 18 is provided with a tuning bar 19 secured thereto, the tuning bar having a screw-threaded bore 20 by means of which its position with relation to the window can be adjusted by means of a screw-threaded rod introduced temporarily into the interior of the section 14 through the evacuating tubulation 17 before the latter is sealed off. The diaphragm 18 provides for the adjustment of the resonance frequency of the cavity between the diaphragm 18 and the window 4, including that necessitated by any departure from a predetermined value by the presence of the di-electric body 10 introduced into the cavity.

FIGS. 4 and 5 also illustrate an alternative way by which the block 10 may be secured into position, the edges 21 of the diaphragm 18 below the point at which the diaphragm is secured to the wall of the waveguide being turned inwards to prevent the block 10 from becoming displaced from its position adjacent the window 4. Preferably a separate spring shim of metal (not shown) is placed between the side of the arc shield 10 and the waveguide to hold the shield firmly in position. Other arrangements for retaining the shield in position may, however, be adopted.

In an alternative arrangement the block may be held in position by nicking the inner wall of the waveguide 14 with a sharp instrument to produce burrs against which the rear of the block may be retained. The block is inserted into position against the burrs prior to the end wall 15 containing the resonant slot, being secured, e.g. by soldering, to the wall of the waveguide section.

A batch of nine TB cells made as shown in FIG. 4, was put on life test at 200 kw. pulse power. All nine cells were satisfactory at over 1,600 hours; a result much superior to that obtained with cells without arc shields.

Although the block 10 has been illustrated as being of rectangular shape, any other suitable shape may be employed provided the concavity in the block is sufficient substantially to enclose the window across which the discharge is to take place. Instead of making the block 10

from one piece of vitreous material, it may be built up in the form of a hollow open-sided box from sheets of vitreous material. For example, ceramic sheet glazed on one face, may be cut into pieces to form the sides and end 5 of a box, the pieces being secured together, after assembly, by heating in a furnace, the glaze melting and subsequently solidifying to secure the pieces together at their edges. It is also permissible for the face of the block or box in which the hollow or concavity 11 is present to be 10 non-planar, if desired.

What we claim is:

1. A T.R. device comprising a section of waveguide, transverse metal walls sealing the ends of said section, at least one of said walls having a window in the form of a resonant slot sealed by glass hermetically fused to the edges of said slot and covering the inner face of said one wall, said section having been evacuated and containing a filling of an inert gas and water vapour, a rectangular hollow block of vitreous material located within said section and being of such size as to allow a space between the inner wall of said waveguide and the outer side walls of said block, said hollow block having an open face on the side thereof arranged adjacent to said window and presenting a concavity toward said window in which concavity said filling is present, and means extending from the walls of said section for retaining said hollow block in proximity to said window spaced from said window transverse wall which cooperating with said spacing from the inner walls of said waveguide provides a space around 20 said hollow block through which a continuing supply of said filling enters said concavity.
2. A T.R. device according to claim 1, in which the hollow in said block is in the form of a depression of cylindrical contour bounded by side walls substantially 25 perpendicular to a plane containing said open face of said block.
3. A T.R. device comprising a section of rectangular waveguide, transverse metal walls sealing the ends of said section, at least one of said walls having a window in the form of a resonant slot sealed by glass hermetically fused to the edges of said slot and covering the inner face of said one wall, said section having been evacuated and containing a filling of an inert gas and water vapour, a rectangular hollow block of vitreous material located within 30 said section and being of such a size as to allow a space between the inner wall of said waveguide and the outer side walls of said block, said hollow block having an open face on the side thereof arranged adjacent to said window and presenting a concavity toward said window in which concavity said filling is present, a wide inductive iris spaced from said transverse wall containing said resonant slot, said iris being secured to the wall of said section and retaining said vitreous member in proximity to 35 said window spaced from said window transverse wall and from said iris so that a continuing supply of said filling enters said concavity.
